CHARLES ZOOK SUTTON, OF PIEDMONT, CALIFORNIA, ASSIGNOR TO INSTOGRAPH LTD., OF OAKLAND, CALIFORNIA, A CORPORATION OF CALIFORNIA

MACHINE BASE

Application filed December 14, 1929. Serial No. 414,067.

My invention relates to a base for such machines as time recorders or calculating machines. More particularly it relates to the construction and assembly of the base.

5 It is the broad object of my invention to simplify the construction and to facilitate the assembly of the base.

The invention possesses other advantageous features, some of which with the foregoing will be set forth at length in the following description where I shall outline in full that form of the machine base of my invention, which I have selected for illustration in the drawing accompanying and forming 15 part of the present specification. In said drawing I have shown one form of machine base embodying my invention, but it is to be understood that I do not limit myself to such form since the invention, as set forth in the 20 claims, may be embodied in a plurality of forms.

In said drawing:

Figure 1 is a bottom view of a machine base, embodying my invention, partially assembled.

Figure 2 is a plan view of a portion of the machine base.

Figure 3 is a cross section through the base portion shown in Figure 2 along the line 3—3.

30 Figure 4 is a perspective view of a foot suitable for use with the base.

Figure 5 is a perspective view of a member and a stud utilized in connection with the base.

35 With such machines as calculating machines, adding machines or time recorders, it is usual to provide feet formed of a suitable material, as rubber upon the base of the machine to protect, against damage, surfaces 40 upon which the machine may be positioned.

These feet have been separately attached to the base of a machine, usually in such a manner that they covered one of the studs utilized to secure the base to the machine casing 45 proper. When it was desired to examine the machine, the several feet had to be removed from the base before the studs could be gotten at to loosen the base from the casing. In accordance with my invention I am enabled 50 to materially simplify the construction of

the base and to secure a foot in position on a machine base at the same time that the base is secured to the machine casing.

In that form of the invention which I have shown in the drawing, machine casing 6 is 55 fitted for the reception of a base 7. A plurality of circular pads 11 are provided at the several corners of the base. These are suitably recessed as at 12 to receive a foot 13 of suitable material so that a surface upon 60 which the machine is positioned will not be damaged and so that the machine will be cushioned. Such a foot is preferably formed of a resilient material as rubber to have a contour similar to that shown in Figure 4. 65

In accordance with my invention, I provide means for securing the foot 13 in position in the recess 12 conjointly with the securing of the machine base to the casing at the point at which the foot is provided. This I have 70 preferably accomplished by utilizing a stud 16 having a threaded portion 17 adapted to engage the ear provided immediately over the pad 11. The stud is also formed with a shoulder 18 adapted to engage the machine 75 base and to cooperate with the threaded portion 17 in drawing the base into the desired engagement with the casing. A portion 19 extending between the shoulder 18 and threaded portion 17 cooperates with the base 80 and machine casing to secure their accurate positioning relative to each other.

The securing of the foot 13 is preferably accomplished by providing an aperture 20 centrally of the foot and of a considerable 85 extent as is shown in Figure 4. Several fins 21 radiate from the aperture and are joined to annular ring 22 forming the outer portion of the foot. This manner of forming the foot affords several advantages among which 90 is that the fins and annular ring cooperate to prevent the machine from sliding with respect to a surface on which the machine is positioned while the weight of the machine is distributed over the surface. 95

To ensure that the foot, when assembled, does not work loose I provide means for retaining it against release until desired. This is conveniently accomplished by the provision of a member 26, preferably in the form of a 100

cross formed by arms 27 as is shown in Figure 5, having an aperture 28 adapted to pass the stud 16, the aperture being off center with respect to the cross. The arms 27 forming the cross engage the several fins 21 and serve to position the foot 13 eccentrically with respect to the stud so that rotation of the positioned foot cannot occur. The considerable extent of the aperture 20 allows the stud 16 to be passed through it readily and does not necessitate the positioning of the foot in a predetermined manner relative to the stud and cross member 26, thus facilitating assembly. As the stud is drawn into engagement with the threaded portion in the ear 9, the foot is drawn into the recess in the pad 11 and, as the machine base is drawn up to the casing, the cross member 26 secures the foot in position. The foot being resilient is tensioned slightly by the drawing up of the stud so that the stud is restrained against accidental rotation by the frictional engagement of the cross and the stud. By providing the resilient foot accurate machining of the various parts is rendered unnecessary since minor variations are cared for by it. Thus the length of the stud between the head and the shoulder 18 need not be as accurate as would be necessary if the foot were not resilient.

When it is desired to examine the interior of the casing, the stud 16 is withdrawn from engagement with the ear. Simultaneously, the foot is released and the base is then readily removed. This construction obviates the several additional parts and operations previously necessary.

I claim:

1. In combination, a stud having a threaded portion and another portion forming a shoulder with the threaded portion, a casing having a threaded portion to receive the stud, a base adapted to be secured to the casing and having a circular recess eccentric with respect to the threaded portion of said casing, a circular foot having an aperture therein for positioning in the recess in said base, and a cross member adapted to be positioned eccentrically on said stud to secure said foot in position, said stud engaging the threaded portion of the casing to secure the foot in position in the recess in said base, the shoulder portion on the stud engaging the base to secure said base to the casing upon engagement of the threaded portion of the stud with the threaded portion of the casing.
2. In combination, a casing having a threaded opening, a base for positioning on the casing, said base having a circular recess therein eccentric with respect to said opening, a resilient foot having an aperture therein, a stud adapted to be passed through the aperture in the foot, said stud being threaded to engage the casing and having a shoulder thereon to engage the base to draw the base and casing together, and means on the stud

for engaging the foot to secure the foot within said recess in the base conjointly with the drawing of the base and casing together.

3. In a device for securing a circular apertured foot to a machine base having a circular recess therein, a member adapted to engage the foot, the member having an aperture therein eccentric with respect to said recess, and a stud for insertion through the apertures in said foot and said member to secure the foot and member to the base whereby the foot is non-rotatably held in the recess in said base.

4. In a device for securing an apertured resilient foot in a pad on a machine base, the foot having fins formed therein, a cross member adapted to be inserted in the foot to engage the fins, the cross member having an aperture offset with respect to the center of the member, and a stud adapted to be passed through the aperture to draw the cross member and foot non-rotatably together.

5. In a combination, a stud having a threaded portion and another portion forming a shoulder adjacent the threaded portion, a casing having a threaded portion to receive the threaded portion of the stud, a base adapted to be secured to the casing, said base having a recess therein eccentric with respect to the threaded portion of said casing, a foot having an aperture therein for positioning in the recess in said base, and a cross member adapted to be positioned on said stud and to engage the foot to secure said foot non-rotatably in position, said stud engaging the threaded portion of the casing to secure the foot in position in the recess in said base, the shoulder portion on the stud engaging the base to secure the base to the casing upon engagement of the threaded portion of the stud with the threaded portion of the casing.

In testimony whereof, I have hereunto set my hand.

CHARLES ZOOK SUTTON.
